UNITED STATES PATENT OFFICE.

NEWTON JACKSON, OF NEWPORT, RHODE ISLAND.

WIRE CLAMP.

Application filed February 21, 1924. Serial No. 694,338.

To all whom it may concern:

Be it known that NEWTON JACKSON, a citizen of the United States, residing at Newport, in the county of Newport and State of Rhode Island, has invented certain new and useful Improvements in Wire Clamps, of which the following is a specification.

This invention relates to the general art of clamps and has more particular reference to a clamp that is generally designed to be used in making wire connections and more particularly for use where secondary overhead electric service wires are tapped to secondary mains which are run on racks along a street.

The primary object of the invention resides in the provision of a clamp of the above character wherein two wires that cross at substantially right angles to each other, may be rigidly connected together and this without the usual necessity of soldering the same, the nature of this clamp being such as to rigidly connect two wires of different sizes and to make a permanent contact between the two wires.

A still further object is to provide a clamp of the above character wherein two cross wires may be joined together without the usual slow process of making wrapped joints and further the invention is such as to enable the clamp to be employed in the connection of wires of varying sizes.

With the foregoing and other objects in view, as the nature of the invention will be better understood, the same comprises the novel form, combination and arrangement of parts hereinafter more fully described, shown in the accompanying drawing and claimed.

In the drawing wherein like reference characters indicate corresponding parts throughout the different views:

Figure 1 is a view partly in end and partly in side elevation of a clamp constructed in accordance with the present invention, the same being shown as actually employed in the connection of two cross wires,

Figure 2 is a top plan view thereof,

Figure 3 is an edge elevational view of one of the clamp members per se, and

Figures 4 and 5 are plan views of the inner sides of the two clamp members comprising the main elements of the present invention.

Now having specific reference to the

drawing, my novel crossed wire clamp embodies the provision of two identically shaped clamp plates 5—5 of any suitable metal and being of general oblong shape as clearly shown in Figures 4 and 5.

Adjacent the opposite ends of each of these clamp members, the same is formed with circular openings 6—6 whereby said clamp members may be joined together in face to face relation through the medium of bolt and nut connections designated generally 7.

In addition to these openings 6—6, each clamp member 5 is formed upon its inner face with a diagonally extending relatively deep and wide V-shaped channel 8 that opens at its opposite ends at the side edges of said clamp plates.

It will be readily appreciated that when these two clamp members 5—5 are placed in face to face contact with each other, the channel 8 in each clamp will extend at direct right angles to the channel of the cooperating plates and in actual use, the cross wires A and B are disposed within the channels of the corresponding plates to extend at direct right angles to each other as clearly shown in Figures 1 and 2 and to be subsequently rigidly joined together at their point of crossing by tightening up upon the nut of the beforementioned bolt and nut connections indicated generally at 7.

From the foregoing, it will be apparent, that I have provided a highly novel, simple and efficient form of wire clamp and one that is well adapted for the rigid connection of a pair of cross wires of widely varying sizes and this without the usual necessity of providing a wrapped joint or other form of soldered connection between said wires and one that will effect an electrical connection between the wires in a manner as efficient as said wrapped or other form of soldered joint.

I do not wish to be limited to the specific shape of the clamp plates 5—5 shown in the views nor the material from which they are formed in view of the fact that in the future practice the shape of these plates may be varied as well as the material from which they are formed without departing from the spirit and scope of the appended claim.

Having thus described my invention, what I claim as new and desire to secure by Letters Patent is:

A clamp device for cross wires compris-

ing a pair of plate members, said members being of the same configuration and the same relative dimension, each member having parallel side edges and provided in the vicinity of its ends with circular openings located midway between the parallel side edges, each member being provided at one of its faces with a channel having its side edges disposed at acute angles to the side

edges of the member, said channel being located between the openings, and the edges of the channel intersecting the edges of the openings at the inner portions thereof and a pair of traction bolts passing through the openings of the members and disposed one at each side of both of the channels.

In testimony whereof I affix my signature.
NEWTON JACKSON.
